UNITED STATES PATENT OFFICE.

WILLIAM F. GREGORY, OF BUFFALO, NEW YORK.

DESIGN FOR A GRATE-BAR.

SPECIFICATION forming part of Design No. 22,739, dated August 22, 1893.

Application filed July 17, 1893. Serial No. 480,761. Term of patent 14 years.

To all whom it may concern:

Be it known that I, WILLIAM F. GREGORY, a citizen of the United States, residing at Buffalo, in the county of Erie and State of New York, have invented and produced a new and original Design for a Grate-Bar; and I do hereby declare the following to be a full, clear, and exact description of the same, reference being had to the accompanying drawings, forming a part thereof.

My invention is a new and original design for a grate bar of which the following is a specification, reference being had to the accompanying drawings which illustrate a grate bar embodying my design.

In the drawings, Figure 1 is a perspective view of the grate bar. Fig. 2 is a top plan view. Fig. 3 is a side elevation of the same.

The grate bar A is formed with a curved upper surface which is provided with a slot a extending longitudinally through the center of the bar at each side of which is a series of inclined slots a'. The central slot is sepa-

rated at intervals by webs a² as shown. At each side of the slot a are depending portions B extending longitudinally of the bar, and at each side of the bar, inclined bracket webs b extend from the under side of the upper part of the bar to one of said depending portions B, the bracket webs being in line with the solid portions a³ between the inclined slots a'.

Other features of my design are cylindrical shaped projecting lugs C at each end of the bar, and a pair of lugs D D parallel to each other, depending from one end of the bar, each being perforated as shown at d.

What I claim is—

The design for a grate bar herein shown and described.

In testimony whereof I affix my signature in presence of two witnesses.

WILLIAM F. GREGORY.
